UNITED STATES PATENT OFFICE.

DOMINGO TORRES GARCIA, OF GUADALAJARA, MEXICO.

CLOCK.

SPECIFICATION forming part of Letters Patent No. 349,878, dated September 28, 1886.

Application filed February 13, 1886. Serial No. 191,806. (No model.)

To all whom it may concern:

Be it known that I, DOMINGO TORRES GARCIA, of Guadalajara, Mexico, have invented a new and Improved Differential Clock, of which 5 the following is a full, clear, and exact description.

The object of my invention is to provide a new and improved clock or time-keeping mechanism, which is constructed with very few 10 parts, indicates the time very accurately, and is not apt to get out of order.

The invention consists in the construction and combination of parts and details, as will be fully described and set forth hereinafter, 15 and pointed out particularly in the claims.

Reference is to be had to the accompanying drawings, forming a part of this specification, in which similar letters of reference indicate corresponding parts in all the figures.

20 Figure 1 is a face view of the mechanism of my improved clock, the outer fixed dial or ring and the outer toothed wheel being removed. Fig. 2 is a cross-sectional view of the complete mechanism, and Fig. 3 is a face view of 25 the same.

The construction of the clock is based upon the principle of differential gearing, which has been applied in the manner to be described.

The anchor escapement or pallet A is mounted 30 on the shaft A', pivoted in the frame B of the clock in the usual manner, and provided with a downwardly-projecting arm, C, forked at its lower end at C', to receive the pendulum-rod D, which is provided at its lower end with 35 an ordinary adjustable bob or weight, D'. The pendulum-rod D, which may be of any preferred style, material, or construction, is suspended from a pivot mounted in a bearing, D'', attached to the frame of the clock; or it may be 40 hung in any other suitable manner. On a spindle or arbor, E, journaled in a suitable bearing attached to the frame of the clock, is mounted 45 a pinion, F, which engages with a cog-wheel, G, journaled in suitable supports and carrying a drum or barrel, H, and on the drum a cord, wire, or cat-gut, J, is secured, having 50 a weight, K, attached to its free end. All these parts are of ordinary construction, and it is evident that an ordinary clock-spring may

On the spindle or arbor E the two toothed wheels L and M are mounted, the inner wheel, L, being mounted rigidly, and the outer wheel, M, being provided with a sleeve mounted rather loosely on the spindle E, and both wheels 55 L and M are engaged by the anchor or pallet A. The inner wheel, L, is provided with a few less teeth than the wheel M, as and for the purpose hereinafter described, and on the face of the inner wheel, L, is produced a circular 60 scale divided into twelve equal parts, and each of said divisions is subdivided into twelve equal parts, so that the inner wheel, L, is divided into one hundred and forty-four parts, the twelve larger divisions representing the twelve 65 hours, and each hour being divided into twelve parts, each of which represents five minutes. The outer wheel, M, is cut out and provided with spokes, so as to permit inspection of the face of the inner wheel, L, and is also provided with a pointer, T, which moves over the circular scale on the inner wheel, L. The outer wheel, M, is also provided on its periphery with a circular scale divided into five parts, each indicating a minute, and each in 70 turn subdivided into sixty parts, making three hundred divisions in all.

With the division on the outer wheel, M, a pointer or index, R, is arranged to register, said pointer being formed or provided on the 80 inner edge of the circular ring S, attached to the frame of the clock and surrounding the outer wheel, M, though placed slightly outward from the same.

The operation is as follows: The weight K, 85 acting on the drum, causes the revolution of the cog-wheel G, whereby the pinion F and its spindle or arbor E are revolved, carrying with them the inner toothed wheel, L, the rotation of which is controlled by the anchor-pallet A. The action of the toothed wheel L on the pallet A causes a swinging of the pendulum, and at each beat of the same a tooth of each toothed wheel L and M is released. Let us suppose that the inner wheel, L, has 95 two hundred and eighty-eight teeth and the outer wheel, M, two hundred and ninety teeth. Then, by the time the wheel L has made a revolution M will have completed its revolution less two teeth, or four beats. Then, if, for ex- 100

ample, the pendulum is adjusted to make two oscillations, or two beats of the pendulum, in thirty twenty-ninths of a second, the outer wheel will make a complete revolution in thirty 5 twenty-ninths times two hundred and ninety, or three hundred seconds, or five minutes, as will be indicated by its change of position with respect to the fixed pointer R. The inner wheel, L, will complete a revolution in thirty 10 twenty-ninths times two hundred and eighty-eight seconds, or one hundred and forty-four twenty-ninths minutes. At the end of one hour from twelve o'clock the wheel M will have made twelve revolutions, while the wheel 15 L will have made twelve one-twelfths revolutions, so that the pointer T on the wheel M will point to 1 on the wheel L, thus indicating one o'clock, and so on. The five-minute fractions of the hour will also be indicated by the pointer 20 T pointing to the small divisions on the wheel L. The minutes and seconds will be indicated by the fixed pointer R pointing to the divisions on the scale on the outer wheel, M. Many other combinations of numbers may be used 25 with equal advantage.

By the differential mechanism the long divisions of time are accurately indicated without the use of the usual multiplying-train.

I lay no broad claim herein to the devices 30 for actuating the differential gear from the motion of the pendulum, as such are embodied in my application No. 191,807, of same date.

Having thus described my invention, what I claim as new, and desire to secure by Letters 35 Patent, is—

1. In a clock, the combination, with the clock-work, of two toothed wheels, of which one has one or more teeth more than the other, and of an escapement anchor lever or pallet engaging 40 with both of the said wheels, substantially as herein shown and described.

2. The combination, with a clock mechanism, of two toothed wheels, of which one has one or more teeth more than the other, and of 45 an escapement anchor lever or pallet engaging with the teeth of both wheels, the wheel having the smaller number of teeth being mounted rigidly on a spindle or arbor, and the wheel having the larger number of teeth being mount-

ed loosely on said spindle or arbor, substantially as herein shown and described. 50

3. The combination, with a cog-wheel, of a weight and cord or spring for revolving the same, a pinion engaging with said cog-wheel and mounted on a shaft, two toothed wheels, 55 one of which is mounted rigidly and the other loosely on the pinion-shaft, the loose wheel having one or more teeth more in its rim than the fixed wheel, and of an escapement anchor lever or pallet engaging with the teeth of both 60 wheels, substantially as herein shown and described.

4. The combination, with a clock-work mechanism, of two toothed wheels mounted on the same shaft, one being fixed and the other 65 loose, the fixed wheel having less teeth than the loose wheel, and an escapement anchor pallet or lever engaging with both wheels, the loose escapement-wheel having part of its face cut out and a circular scale formed around the 70 opening, and the fixed wheel with the smaller number of teeth having a circular scale produced on its face, substantially as herein shown and described.

5. The combination, with a clock-work 75 mechanism, of two toothed wheels mounted on the same shaft, one being fixed and the other loose, the fixed wheel having fewer teeth than the loose wheel, an escapement pallet anchor or lever engaging the teeth of both wheels, the 80 front loose wheel provided with the larger number of teeth having part of its face cut out to form an opening through which the rear wheel having the smaller number of teeth shows, a pointer formed on the front loose 85 wheel having the larger number of teeth and projecting over a scale on the face of the inner fixed wheel having the smaller number of teeth, and of a casing or frame having a pointer projecting over the scale formed on the face 90 of the front loose wheel with the larger number of teeth, substantially as herein shown and described.
